[57] **CLAIM**

The ornamental design for a foot lever for motorcycles, as shown and described.

DESCRIPTION

FIG. 1 is a top front perspective view of a foot lever for motorcycles showing our new design;

FIG. 2 is a top plan view of FIG. 1, the bottom being substantially a mirror image thereof except that the circular projection shown on the top right end is omitted therefrom;

FIG. 3 is an end elevational view of FIG. 1; and

FIG. 4 is a rear elevational view of FIG. 1 on a reduced scale.

FIG. 4

FIG. 1

FIG. 2

FIG. 3
